UNITED STATES PATENT OFFICE.

GEORGE W. COLLINS, OF HOLYOKE, MASSACHUSETTS.

HINGED SEAT AND COVER.

1,264,612.

Specification of Letters Patent. Patented Apr. 30, 1918.

Application filed February 9, 1915. Serial No. 7,016.

To all whom it may concern:

Be it known that I, GEORGE W. COLLINS, a citizen of the United States, residing at Holyoke, in the county of Hampden, State 5 of Massachusetts, have invented new and useful Improvements in Hinged Seats and Covers, of which the following is a specification, reference being made to the accompanying drawings and the letters of 10 reference marked thereon.

The object of the invention is to provide an improved hinge construction whereby the seat may be hingedly connected to its support, such as a water-closet bowl, and 15 the cover hingedly connected to the seat by hinging elements which are wholly independent of and separate from the hinging elements by which the seat is connected to its support, the construction being such that 20 whether the cover is applied to the seat or detached therefrom there is no metal exposed to the danger of corrosion, and the sightliness and symmetry of the parts and their sanitary condition unimpaired. The 25 invention consists of a seat having its own individual hinge connection with its support, and provided with a cover hinging element which is wholly separate from and independent of the seat hinging element so 30 as to receive and secure a cover which is detachable at pleasure; and the invention further consists in certain details of construction, as I will proceed now to explain and finally claim.

35 In the drawings Figure 1 is a perspective view of my improved construction, and Fig. 2 is a vertical section, on a larger scale, of the rear portion of the seat and cover showing the hinge construction in detail. Fig. 3 40 is a transverse section illustrating a modification in the hinging of the cover, and Fig. 4 is a transverse section showing the cover and pintle removed and the plugs of Fig. 3 used to close the pintle-opening in the seat 45 projection or block.

The seat *a* and cover *b* may be of any usual or approved construction, and are preferably covered with celluloid or other suitable sanitary or protective material. If desired, these parts may be built up of sections 50 suitably matched as indicated in the drawing and held together, by fastenings, such as the concealed or blind dowels *h* shown in connection with the seat, Fig. 1. The cover 55 *b* has the rearward extensions *c* and these extensions straddle an upward projection or

block *d* on a rearward extension *e* of the seat, and the extension *c* and projection *d* are pierced transversely to receive a suitable pintle *f* by which the seat and cover 60 are hingedly connected. The pintle may be long enough to extend beyond the extensions *c* and be provided with the screw-threaded ends to be engaged by knob-like finish nuts *f'*, as in Figs. 1 and 2. The 65 projection *d* may be secured to or made integral with the seat extension *e*. The extension *e* is provided with transverse holes or openings to receive the pintles of the seat-hinging elements *g*, and these hinging 70 elements serve to connect the seat with its support, such as a water closet bowl.

The whole surface of all the parts preferably is covered with celluloid or other sanitary covering, and thus in addition a 75 perfectly smooth surface may be obtained. The only metal parts employed are the pintle *f* and hinge elements *g*. The pintle may be of less length than the total distance between the outer surfaces of the sides of 80 the extensions *c* as shown at *f''*, Fig. 3, and the spaces thus left in the pintle openings in these extensions may be plugged with plugs *i*, *i*, Fig. 3, which may be covered with celluloid or like finish or covering. 85 So also the members *g* may be covered with celluloid or some other non-metallic or non-corrodible substance.

It will be seen that by the construction herein described, the employment of metal 90 parts is reduced to a minimum, and that such metal parts as are employed are covered where exposed with a substance such as that used on the seat extension and the projection *d* and the rearward cover extension, so that 95 the objectionable appearance of corroded metal is avoided, and the cost of manufacture reduced. Moreover, and this is to be particularly noted, the seat and the cover are hinged independently of one another, so that 100 the breaking or disarrangement of the hinging elements of one part does not interfere with the operation of the other part. The cover may be detached from the seat without affecting the seat hinging elements, and without 105 destroying the sightliness or symmetry of the seat, since the projection *d* in no wise suggests a hinge, and is in no wise connected with the seat hinging elements. This detachability of the seat cover is advantageous in many additional ways. For example, 110 the cover is not always desired by the owner

or builder of a house or other edifice, and it may be omitted at a reduction in initial cost to the purchaser, who may wish at some future time to install the cover. Some 5 factory inspectors insist upon sanitary grounds, on the omission of covers, while others require them. Trade union officials likewise require one thing in one place and another in another place. Obviously, therefore, 10 a water closet top that may discard its cover without in the least affecting its utility or appearance is of great practical utility, especially when its construction is such that the cover may be omitted or supplied 15 without any alteration of the mechanism of the top, as is the case with my invention. A manufacturer or dealer need provide only one style of top to meet all these various requirements, and keep a stock 20 of covers proportional to ascertainable averages of need of them, or make them to order without discarding present installations or interrupting their use. When the seat cover is thus removed, the pintle hole or holes in 25 the projection d may be plugged, as shown in Fig.4, so as to avoid the accumulation of dirt, or otherwise rendering the seat unsanitary. Furthermore, the arrangement of one hinge element above the other avoids the 30 danger of the seat and cover rubbing against each other when the seat is raised with the cover resting on it, as might result were the pivotal points in the same horizontal plane. It is immaterial whether the pivotal points 35 or hinging elements are in the same vertical plane, and in some instances it is preferable that they be not in the same vertical plane, and with my construction it is possible to conveniently arrange these hinging elements 40 or pivotal points out of vertical alinement by locating the projection d farther toward the front. One of the advantages of such an ar-

rangement is that provision is made for clearance back of the cover when opened or raised. In some cases it is desirable to turn 45 the cover backwardly so that it may occupy a position parallel with the seat, and this is possible with the construction herein described.

What I claim is:—

1. The combination of a seat having a rearward extension, means for hingedly mounting said seat in place, an upward projection upon said seat, and a cover hingedly mounted upon said projection, independently of the hinging elements of the seat and detachable therefrom at pleasure without impairing the sightliness of the seat or dismounting or exposing wholly or in part the seat hinging elements. 50

2. The combination of a seat having a rearward extension, means for hingedly mounting said seat in place, an upward projection fixedly applied to said rearward extension, a cover having rearward extensions 65 adapted to engage said seat projection, and means independent of the seat hinging elements for hingedly connecting the seat projection and the cover extensions, whereby the cover may be detached and removed without 70 affecting the seat hinging elements or impairing the sightliness of the seat.

3. The combination of a seat having a rearward extension, hinge posts having pintles engaging said extension, a projection 75 rising from said extension, a cover having rearward extensions alined with the seat projection and provided with pintle openings, and pintles passed through the cover extensions and into the seat projection.

GEORGE W. COLLINS.
